ATTORNEY.

UNITED STATES PATENT OFFICE.

JOHN W. CASEY, OF SISTERSVILLE, WEST VIRGINIA.

FEED-WATER HEATER.

SPECIFICATION forming part of Letters Patent No. 627,980, dated July 4, 1899.

Application filed October 3, 1898. Serial No. 892,495. (No model.)

To all whom it may concern:

Be it known that I, JOHN W. CASEY, of Sistersville, in the county of Tyler and State of West Virginia, have invented certain new and useful Improvements in Feed-Water Heaters; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to feed-water heaters which are located in the furnace of steam-boilers, and has for its object the better circulation of the water through the heater whether the feed-water is being fed to the boiler or cut off, and also to prevent the deposit of sediment on the bottom of the heater by the location of the feed-pipe in the heater, and other details of construction, as will hereinafter appear.

This device is an improvement on my invention shown in patent granted to me June 23, 1896, No. 562,574.

Referring to the drawings accompanying this specification, Figure 1 shows a side elevation of the pipe connections to the heater; Fig. 2, a vertical section through the boiler and furnace on line xx . Fig. 3 shows a detail of feed-water-pipe connection to the heater, and Fig. 4 a modification of the heater.

In the drawings, A is the furnace or fire-box; B, the tube-sheet; C, the grate-bars, and D the feed-water heater.

The heater is preferably cylindrical in form and provided with supporting-necks E E', which rest in the walls of the furnace. It must be understood that this heater is adapted for any furnace and may rest on the brick walls of the same or on the water-legs of a locomotive-boiler, as shown, the neck on each end of the heater, neck E being on the upper side of the discharge end of the heater and the neck E' being on the bottom of the inlet end for the feed-water or circulation from the water-leg of the boiler; but this connection may for boiler circulation be connected to the bottom of the boiler, as is commonly done to produce circulation in boilers. As shown in my patent, the heater is shorter than the

width of the furnace, with one neck longer than the other, so as to permit the insertion and removal of the heater without disturbing the construction of the boiler or furnace.

H is a nipple screwed into the T-coupling G, which in turn is secured to the neck E' by the short pipe F. Secured to the inner end of the nipple is the perforated feed-pipe I, which when the parts are in position will lie near the bottom of the heater, whereby the entering feed-water will wash away any sediment that may attempt to deposit on the bottom of the heater. To the outer end of the nipple is attached the feed-pipe K, leading from the injector or pump. To the upper nipple E is attached the discharge-pipe L, which leads to the top of the boiler near the water-line.

To the bottom part of the T-coupling is attached the circulating-pipe M, which leads to the bottom of the boiler or water-leg. This pipe is provided with a stop-valve N, which may be shut off should the heater get out of order.

The heater shown in Fig. 4 is provided with two outlets and two inlets, so that two injectors or pumps could be used at the same time.

The operation of the device is readily understood. The water entering through the pipes K and I into the bottom of the heater keeps the water agitated at that point, preventing any sediment collecting there and also compelling the water to circulate in the heater, so that it may become highly heated for passing out through pipe L into the boiler. The entering of the feed-water causes a circulation of the water from the bottom of the boiler to the top through the heater, and also there is an automatic circulation when the feed is shut off.

What I claim is—

1. The combination of a steam-generator with a removable feed-water heater provided with necks located at the top of one of its ends and at the bottom of the other for supporting the heater in the fire-box, a feed-water pipe entering the lower neck and a circulating-pipe connected to the said lower neck and the bottom of the boiler and means for connecting the heater to the upper water-space of the boiler, substantially as described.

2. In a feed-water heater for boiler-furnaces, the combination with the heater provided with an upper outlet entering about the water-level of the boiler and a lower inlet at its opposite ends, of a perforated feed-pipe smaller than the interior diameter of the inlet and entering the said inlet and located near the bottom of the heater and a circulating-pipe connected to the inlet to the heater and to the bottom of the boiler, substantially as described.

3. In a feed-water heater the combination of a circulating-pipe leading from the bottom of the boiler to the bottom end of the heater,

with a feed-pipe entering the said heater through the circulating-pipe near the bottom thereof and means for connecting the other end of the heater with the upper water-space of the boiler and secured to a nipple in the coupling of the circulating-pipe, substantially as described.

In testimony that I claim the foregoing as my own I affix my signature in presence of two witnesses.

JOHN W. CASEY.
